(57) **CLAIM**

The ornamental design for a pedal bin as shown and described.

DESCRIPTION

FIG. 1 is a front, right and top perspective view of a pedal bin, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is a front, right and top perspective view of a second embodiment of a pedal bin.

FIG. 11 is a rear, left and bottom perspective view of the second embodiment of the Pedal bin of FIG. 10.

FIG. 12 is a front elevation view of the second embodiment of the pedal bin of FIG. 10.

FIG. 13 is a rear elevation view of the second embodiment of the pedal bin of FIG. 10.

FIG. 14 is a left side elevation view of the second embodiment of the pedal bin of FIG. 10.

FIG. 15 is a right side elevation view of the second embodiment of the pedal bin of FIG. 10.

FIG. 16 is a top plan elevation view of the second embodiment of the pedal bin of FIG. 10.

FIG. 17 is a bottom plan elevation view of the second embodiment of the pedal bin of FIG. 10; and,

FIG. 18 is an enlarged view of detail 18 in FIG. 10.

The broken lines depict portions of the pedal bin that form no part of the claimed design. The dot-dash broken lines in FIGS. 1, 9, 10 and 18 depict the boundaries of the enlargements that form no part of the claimed design.
